UNITED STATES PATENT OFFICE.

JULES ROBINET, OF SUIPPES, FRANCE.

IRRIGATING APPARATUS.

SPECIFICATION forming part of Letters Patent No. 289,448, dated December 4, 1883.

Application filed December 30, 1882. (No model.) Patented in France June 25, 1881, No. 143,620; in Italy November 6, 1881, No. 13,517; in Austria November 7, 1881, No. 10,726, and in Spain November 14, 1881, No. 2,009.

To all whom it may concern:

Be it known that I, JULES ROBINET, of Suippes, France, have invented a new and useful Improvement in Irrigating Apparatus, (for which I have obtained a patent in France, bearing date June 25, A. D. 1881, No. 143,620; Italy, dated November 6, 1881, No. 13,517; Austria, dated November 7, 1881, No. 10,726; Spain, dated November 14, 1881, No. 2,009,) 10 of which the following is a specification.

My invention relates to apparatus for irrigating land, and will be described by means of the accompanying drawings, in which—

Figure 1 represents a side elevation and partial section of the driving mechanism, pumps, and air-vessel, while Fig. 2 is a side elevation of an irrigating-tube with supports.

A crank-shaft, D, with fly-wheel E, is mounted on a beam, U, which supports also the fulcrum C' for the lever C. The latter is set in motion from the crank-shaft by a connecting-rod, B, and serves to drive the two pumps A A' by means of rods A" A", so that their pistons move in opposite directions. Water is drawn into the pumps through a pipe, F, and delivered by a pipe, G, into an air-vessel, I, from which it flows into the pipes K K' through openings J J'. There may be one, two, or more such pipes K K', each being provided 20 with a cock or valve, S, and led underground 25 to the point where the water is required. The inlet to the air-vessel is provided with an inlet-valve, h, which, like the valves and pistons of the pumps, may be of any suitable known 30 construction. At any convenient point of the underground pipe K a vertical pipe, L, is led upward, which pipe is bent horizontally at the

top P. There may be one or more vertical pipes L branched off from each horizontal pipe K. Over the upper end P fits the end 40 of the irrigation-tube O, which is supported by several stands, q, and provided with water-jets n, or nozzles, at suitable intervals. By turning the horizontal tube O by means of the hand-wheel R, attached to it, the direction of 45 the water-jets may be altered, and for altering the stroke of the pumps A A' the upper end of the lever C is provided with a series of holes, to any of which the pin of the connecting-rod 50 may be attached.

What I claim as my invention is—

1. In irrigating apparatus, the combination of two pumps, A A', driving-lever C C, provided with means for varying the stroke, means for setting the lever in motion from a driving-shaft, suction-pipe F, discharge-pipe G, air-vessel I, provided with an inlet-valve, h, and water-conduit pipes K K', provided with valves or cocks S, substantially as described. 55

2. In irrigating apparatus, the combination of a water-conduit pipe, K, with one or more upright branch pipes, L, each provided with a cock or valve, S, and a horizontal outlet, P, an irrigation-tube, O, supported on stands q, provided with water-jets along the pipe, and 60 with means for turning the tube around the outlet P, substantially as described. 65

In testimony whereof I have signed this specification in the presence of two subscribing witnesses.

JULES ROBINET.
